UNITED STATES PATENT OFFICE.

HARRY S. JARBOE, OF TRENTON, NEW JERSEY, AND PHILIP KELLER, OF SPRINGFIELD, MASSACHUSETTS.

COIN-OPERATED MACHINE.

SPECIFICATION forming part of Letters Patent No. 744,921, dated November 24, 1903.

Application filed September 28, 1901. Serial No. 76,900. (No model.)

To all whom it may concern:

Be it known that we, HARRY S. JARBOE, residing at Trenton, in the county of Mercer and State of New Jersey, and PHILIP KELLER, residing at Springfield, in the county of Hampden and State of Massachusetts, citizens of the United States, have invented a new and useful Improvement in Coin-Operated Machines, of which the following is a specification.

10 This invention relates to coin-operated machines, the object in view being to provide a machine especially adapted for the sale of small single articles, such as cigars, the machine having combined therewith indicating 15 devices in duplicate for the purpose of displaying simultaneously to the customer or purchaser and the salesman the number or nature of the article or articles purchased. The coin-operated mechanism is of such nature 20 that it may be actuated by coins of different denominations, sizes, and weights, which may be easily and quickly removed by the salesman as soon as the indicating devices have performed their work and prior to the 25 delivery of the purchased article or articles to the customer.

With the above and other objects in view, the nature of which will more fully appear as the description proceeds, the invention consists 30 in the novel construction, combination, and arrangement of parts, as hereinafter fully described, illustrated, and claimed.

In the accompanying drawings, Figure 1 is a perspective view of a coin-operated machine 35 constructed in accordance with the present invention. Fig. 2 is a rear elevation of the same, partly in section. Fig. 3 is a vertical transverse section through the machine. Fig. 4 is a horizontal section taken in line with the 40 arbor of the indicating-hands or on the line 4 4 of Fig. 2.

Like reference-letters designate corresponding parts in all figures of the drawings.

Referring to the drawings, A designates a 45 suitable supporting-base provided with suitable means for anchoring or fastening the same to a table, counter, or other support, such means being shown for convenience as consisting of eyes A', adapted to receive 50 screws A², which pass therethrough into the table or support, as shown in Fig. 1. Ex-

tending upward from the base A is a stand or pedestal B, the upper part of which is substantially square or diamond-shaped and constitutes the main body or frame of the machine. The stand or pedestal B is shown as connected with the base A by means of tenons B'.

The front of the frame or body of the machine is provided with a circular recess B², in which is placed a dial C, the face of the dial being graduated and also provided with radially-disposed marks or large graduations, which may be variously colored, if desired. The rear side of the body or frame is also 65 provided with a circular recess D, which is rabbeted, as shown at d, to form a seat or rest for a second dial, C', corresponding in all particulars with the dial C, hereinabove referred to. When the dial C' is placed in position 70 so as to rest against the shoulder formed by the rabbet d, a space is left behind the dial C' or between said dial and the solid or imperforate portion d² of the frame or body of the machine.

A coin chute or channel E is arranged at the top of the frame, opening at the extreme upper central portion thereof and extending from thence downward and communicating with the space d', said coin chute or channel 80 E being enlarged or flared, as shown at E', where it communicates with the space d'.

Extending downward from the bottom of the space d' is another coin chute or passage, F, the upper end portion F' thereof being 85 flared, as shown, to facilitate the reception of coins therein. The two passages E and F are arranged diametrically opposite in vertical alinement with each other, while beneath the discharge end of the passage F the base A 90 and stand or pedestal B are hollowed out or recessed, as shown at H, to form a coin-receiving pocket. At the front of the machine the coin-receiving pocket is covered by means of a plate or block I. At the back said recess or pocket is left exposed, as shown in Fig. 3, and the pocket H extends back of the plane of the pedestal or stand, so as to enable the salesman to extract the coins as fast as they are deposited therein.

Journaled centrally of the frame and dials C and C' is an arbor K, provided at or near

its opposite ends with indicating hands or pointers L and L', rigidly attached thereto. These hands or pointers travel over the faces of their respective dials at the front and rear 5 of the machine, and being set exactly in line with each other they indicate the same graduations or marks on the dial to both the salesman and purchaser.

Mounted fast on the arbor and within the 10 space d' is a coin-operated wheel or disk M, said disk being slightly less in thickness than the width of the space d', so as to revolve freely. The wheel or disk M is provided with a series of laterally-projecting arms or spokes 15 M', which reach nearly to the outer wall or periphery of the recess and have their ends reversely beveled or tapered and pointed, so that a coin placed in the machine must necessarily pass to one side or the other of the 20 uppermost arm or spoke. The said arms or spokes serve as pockets or rests for the coins fed to the machine, and the weight of the coin serves to impart rotary motion to the wheel or disk M and at the same time to the indicating 25 hands or pointers, it being immaterial in which direction the wheel is actuated by the coin. When the coin reaches the lowermost point of the space d', it enters the base through the channel F and drops into the 30 coin-pocket H. The disk, however, will continue to rotate after being relieved of the weight of the coin, and that graduation on the dial at which the pointer finally stops will indicate to the salesman the character of the 35 article to be delivered to the purchaser. The circular recesses at the front and back of the machine are covered by means of glass panels or plates N, held in place by some such means as beading-strips O, said plates serving to protect 40 the operative parts of the mechanism and prevent unauthorized tampering therewith.

From the foregoing description it will be seen that the space d', in which the wheel M revolves under the influence of the coins, 45 comprises for one of its side wheels the dial C' and for its other or opposite and inner side wall the solid central portion d² of the

frame or body of the machine. The coins are thus caught between the adjacent arms or spokes of the wheel and are confined between 50 the front and rear walls of the space d', one of said walls consisting of the dial C'. By removing said dial C' access can be had immediately to the wheel M, so as to free the same in case said wheel becomes jammed or in case 55 the coins become wedged or congested in the space d' by reason of too many coins being deposited in the machine at one time. In restoring the dial C' to its place it comes in contact with the shoulders d, thus preventing the 60 dial from being pushed too far inward, so as to interfere with the operation of the coin-actuated wheel.

Having thus described the invention, we claim as new— 65

In a coin-operated device, the combination of a base provided with a coin-pocket, a stand or pedestal thereon provided with a rabbeted circular recess, a dial seated in said rabbeted recess and forming one of the side walls of 70 the wheel-cavity, a wheel rotatably mounted in said cavity and having reversely beveled and pointed arms with intervening open-sided spaces forming coin-pockets, the sides of which are formed by the stationary opposite walls 75 of the cavity in which the wheel works, an arbor for said wheel, dials at opposite sides of said wheel, and pointers on said arbor movable over the faces of the dials, the machine-frame being provided with coin-passages leading 80 to the wheel and from the wheel to the coin-pocket in the base, substantially as described.
